UNITED STATES PATENT OFFICE.

JOSEPH S. BEEMAN, OF LONDON, ENGLAND.

MAGNETO-ELECTRIC MACHINE.

SPECIFICATION forming part of Letters Patent No. 288,915, dated November 20, 1883.

Application filed February 28, 1883. (No model.) Patented in England July 20, 1882, No. 3,455; in France January 18, 1883, No. 153,192; in Belgium January 24, 1883, No. 60,246, and in Austria-Hungary May 1, 1883, No. 4,877 and No. 18,061.

To all whom it may concern:

Be it known that I, JOSEPH SAMUEL BEEMAN, of 67 Strand, London, England, have invented new and useful Improvements in Magneto-Electric Machines, (for which I have obtained patents in England, No. 3,455, dated July 20, A.D.1882, and in France, No. 153,192, dated January 18, A. D. 1883,) of which the following is a specification.

10 The improvements relate to machinery for removing from the armature of a continuous-current dynamo or magneto electric machine certain sections of the circuit or circuits when they cease to be active in producing current, 15 and replacing these sections into the circuit or circuits as they arrive at the active points in the magnetic field by means of insulated stops or contact-pieces fitted with metallic rubbing-surfaces at portions of their length or width, 20 so that said surfaces connect and complete the circuit or circuits through the active portion or portions of the armature, and so saving power by cutting out the inactive portions of the armature.

25 The invention is performed by dividing, when necessary, the metallic conductor composing the armature into any number of sections, the last end of one section and the first end of the next section, or any convenient arrangement of series or groups of sections, being brought into electrical contact by means of springs or equivalents for impinging, and these armature-sections which are not active in producing current are removed from the 30 circuit or circuits by the action of the springs which make and break contact with the interposed rubbing-surfaces when the armature is rotated.

35 The accompanying drawings will serve to 40 illustrate the mode of performing the invention.

Figure 1 is an elevation of an armature, and Fig. 2 is a plan view of a commutator (unfolded) constructed according to my invention, and shown in end elevation at Fig. 3 and plan at Fig. 4. Figs. 5 and 6 are plan views of modifications of a commutator, (unfolded,) and Fig. 7 is a longitudinal section of Fig. 6. Fig. 8 is an armature in which the opposite

sections of metallic conductor are connected 50 in series, and Figs. 9 and 10 are unfolded views of commutator adapted to Fig. 8.

A is an armature-ring. Y is an insulated hub or carrier for the springs or rubbing-surfaces *b c d e f g h i* and *s r q p o n m l*, which 55 are arranged around the periphery of the carrier in two rows, as shown. In connection with the rotating carrier thus armed with springs or rubbing-surfaces is employed a fixed or stationary insulating-ring, preferably made 60 in two parts, K K', upon which are secured insulated metallic contact-pieces, with their external circuit-connections, M L N P.

In the arrangement shown in the drawings the insulating-ring occupies a position intermediate between the two rows of revolving springs, and the contact-pieces are arranged upon the sides of the ring—that is to say, those faces of the ring that are at right angles to the axis of revolution of the carrier. Of the contact-pieces two, L N, are on one side face of the ring, and are acted on by one row of revolving springs, and two, M and P, are on the opposite side face of the ring, and are acted on by the other row of revolving springs. The 75 insulating-ring is held fixed or stationary by means which will permit it to be adjusted when desired. The ring, as before said, is preferably made in two parts, K K', this being with a view to permit of the independent adjustment of the pair of contact-pieces on each side, and these parts are mounted on and held by the adjusting-bars X X'.

B, C, D, E, F, G, H, and I are sections of metallic conductors on the armature, the first 85 and last ends, *b'*, &c., being connected with their corresponding letters of reference on the commutator or the modifications thereof, as indicated by dotted or broken lines. When the armature and commutator rotate in the direction of the arrow, the springs *b c d*, &c., and *m n o*, &c., as in Fig. 2, successively make and break contact with the circuit at L and M and at N and P. In Figs. 5, 6, and 7 the revolving springs are replaced by revolving 90 rubbing-surfaces, and the fixed contact-pieces shown in Fig. 2 are replaced by fixed scratch-brushes or other springs, as shown. When I

connect the opposite sections of the metallic conductors in the armature in series, as in Fig. 8, the first and last ends of these series being connected with their corresponding letters of reference in the commutator or modification thereof, as shown in Fig. 9 or 10, for instance, the springs or their equivalents make and break contact with the circuit at L and M only, and I only have half the number of revolving springs or their equivalents, and N and P are consequently dispensed with.

I claim as my invention—

1. In dynamo or magneto electric machines, a commutator consisting of a revolving insulated hub or carrier armed with springs, or their equivalent, arranged in two rows and connected with the coils of the armature, as hereinbefore described, in combination with a stationary insulator provided with contact-pieces, or their equivalent, of which one half make contact with one row of springs and one half make contact with the other row of springs during the revolution of the carrier for the purpose of including in the circuit the

armature-coils only as they arrive at the active points in the magnetic field, and cutting out said coils as they arrive at an inactive portion of their revolution, all substantially as hereinbefore set forth.

2. The two-part stationary adjustable insulator-ring provided with contact-pieces, of which one half are carried by each part, in combination with the revolving insulated carrier furnished with contact springs or surfaces connected with the coils of the armature, as hereinbefore described, and arranged in rows upon the carrier, to operate in connection with the contact-pieces on the two-part ring, substantially as and for the purposes hereinbefore set forth.

In testimony whereof I have signed this specification in the presence of two subscribing witnesses.

J. S. BEEMAN.
